UNITED STATES PATENT OFFICE.

GEORGE HOLMES COCKS, OF ASHLAND, KENTUCKY.

CRADLE-SUPPORTING ATTACHMENT FOR BEDS.

1,190,380.

Specification of Letters Patent. Patented July 11, 1916.

Application filed May 29, 1915. Serial No. 31,277.

To all whom it may concern:

Be it known that I, GEORGE H. COCKS, a citizen of the United States, residing at Ashland, in the county of Boyd and State of Kentucky, have invented certain new and useful Improvements in Cradle-Supporting Attachments for Beds, of which the following is a specification, reference being had to the accompanying drawings.

10 My invention relates to cradles and means for supporting them, and particularly to a cradle and supporting attachment so designed that the attachment may be fastened to a bed post and support the cradle therefrom.

15 A further object of my invention is to so form the attachment that the cradle may be swung over the bed or outward therefrom.

20 A further object of my invention is to so hang the cradle that the cradle may be swung either laterally or longitudinally.

25 Still another object of the invention is to provide a cradle supporting device of the character above described in which the cradle may be vertically adjusted so that the cradle may be swung entirely over the bed.

Other objects will appear in the course of the following description.

30 My invention is illustrated in the accompanying drawings, wherein:

Figure 1 is a side elevation of one form of my cradle supporting device; Fig. 2 is a detailed sectional view of the end of the supporting arm and the bed post clamp; Fig. 3 is an elevation of another form of my cradle supporting device, partly broken away; Fig. 4 is a section on the line 4-4 of Fig. 3.

35 In Figs. 1 and 2, I show one form of my device, and in these figures A designates an ordinary iron bed having a bed post B terminating at its upper end in a head d. In this case the cradle supporting attachment comprises the supporting bar 2, which is 40 preferably tubular and interiorly screw threaded at its inner end. Coacting with this interiorly screw-threaded end is a split clamping ring, designated 3, formed in two sections, each section having a complementary shank, these complementary shanks when placed together being insertible within the tubular end of the supporting bar 2

and having screw threaded engagement therewith, as illustrated in Fig. 2. The outer end of the bar 2 is supported against 55 downward movement by a downwardly and rearwardly extending brace 4, the inner end of which brace is formed to partially embrace the post B and have rotary motion thereon. Depending from the bar 2 are the 60 longitudinally spaced supporting hooks 5.

The cradle 6 is preferably made of open-work construction, as for instance wire network, and is elongated in form and the ends of the cradle are supported from the hooks 65 5 by means of chains or other flexible connections 7, and disposed in these flexible connections are the helical springs 8. It is to be noted at this point that the supporting connections 7 of the cradle are disposed at 70 the ends of the cradle and that they extend upward and outward so that access may be readily had to the cradle, and furthermore, so that longitudinal tipping of the cradle may be prevented. A split collar 9 is pref- 75 erably disposed upon the post B above the rail C, and this collar supports the inner terminal end of the supporting bar 2 and prevents the attachment from slipping downward upon the bed post.

80 In Figs. 3 and 4, I show another form of my invention which is designed to be used with metal beds, in which the bed post and cross bar are formed in one piece, or in case the bed post is not high enough to permit 85 the cradle to be swung fully over the bed. In these figures 10 designates what I call an emergency post which is preferably tubular and formed at its upper end with the collar 11, preferably screw threaded upon 90 the post. This emergency post is held rigidly connected to the bed post B' by means of a plurality of clamps 12. These clamps, as illustrated in Fig. 4, comprise oppositely disposed confronting members con- 95 nected by a clamping bolt 13 and formed at their ends with semicircular collars or jaws. The inner faces of these jaws may be lined with felt or other soft substance so as not to injure the bed post. The inner set of jaws 100 on the clamping members is adapted to engage the bed post and the outer set is adapted to engage and support firmly the supplementary post 10. The arm or bar 14 which

supports the cradle and which corresponds to the arm or bar 2 previously described at its ends is provided with a T or head 15. One end of this T-shaped head 15 is adapted 5 to be inserted in the tubular post 10 and have rotative engagement therewith. The outer end of the arm or supporting bar 14 is supported by means of a brace 16, preferably made of half inch tubing, this brace at 10 its inner end being formed to partially embrace the post 10. Preferably, this brace is curved, as illustrated, so as to be out of the way of the cradle itself. The cradle 17, like the cradle previously described, is preferably formed of wire, though not necessarily so, and is supported from the hooks 18 carried by the arm 14 by means of connections 15, helical springs being inserted in these 19, connections.

20 It will be seen that with both forms of my invention the cradle may be readily swung in over the bed or swung out therefrom farther, that the cradle is prevented from tipping by reason of the cradle being supported at its opposite ends and by diverging chains 25 19 which are engaged with the opposite sides of the cradle. Thus there is no danger of the baby falling out of the cradle. In both forms of my invention the swinging supporting arm is adapted to support a mosquito-netting or fly screen inasmuch as the arm extends parallel to the cradle itself. In Fig. 3 it will be seen that the connections 30 19 extend upward and outward in divergent 35 relation so as to permit easy access to be had to the cradle. It will be noted that the cradle may be swung, by a person lying in the bed, either transversely to its length or longitudinally, and that by the use of the 40 contractile springs the cradle may be given a gentle up and down movement.

The brace 4 in the construction shown in Fig. 1 and 16 in the construction shown in Fig. 3 is of great importance. This brace 45 prevents the weight of the crib and baby from depressing the supporting arm, bending it and marring the bed, and the brace at the same time prevents the accidental detachment of the supporting arm. Thus in 50 Fig. 1 the supporting member B is formed at its upper end with a head b. This prevents the vertical movement of the arm 2 to detach the arm 2 from the bed post, and in order to unscrew the tubular member 2 from 55 the clamp 3 it is necessary to disengage the brace 4 from the bed post. This may either be accomplished by having the brace 4 slightly yieldable or by having a loose engagement between the jaws 3 and the bed post. In Fig. 3 the same object is accomplished but in a slightly different manner. The distance between the lower end of the 60 brace 16 and the clamp member 12 is less than the distance between the downwardly

projecting end of the T-shaped member 15 65 and the collar 11. As a consequence the supporting arm 14 cannot be lifted out of its engagement with the member 10 until the clamp 12 has been shifted slightly upward so that the distance between the lower end 70 of the brace is greater than the distance between the lower end of the head 15 and the collar 11. This clamp 12, therefore, forms a stop limiting the vertical movement of the arm 14 of the brace 16 and as long as this stop 75 is in place the brace 16 forms a means preventing the accidental detachment of the supporting arm from the vertical supporting member as well as acting to support the outer end of the arm itself. 80

While I have illustrated certain details of construction which I have deemed to be particularly effective, and have illustrated a construction which is very cheap to make and easy to be put up, I do not wish to be 85 limited to these details as it is obvious that many changes might be made therein without departing from the spirit of my invention.

Having described my invention, what I 90 claim is:

1. In a cradle supporting attachment, the combination with a vertically disposed supporting member having a stop, of an arm rotatably and detachably engaged with the 95 supporting member and a brace extending downward and inward from the arm, said brace at its lower end being formed to partially and loosely embrace the supporting member and being thereby detachably and 100 rotatably engaged therewith, and said brace further acting to prevent the detachment of the arm from the supporting member until the brace is disengaged from the supporting member, said stop limiting the upward 105 movement of the supporting arm and brace and a cradle swingingly supported by the arm.

2. A cradle supporting attachment for beds comprising a vertically disposed supporting element, a cradle supporting arm tubular at one end, a member embracing the element and carried by the screw threaded end of the arm, a brace extending downward and inward from the outer end of the 110 arm and partially embracing the supporting element and thereby having rotative engagement with the vertical supporting element, a cradle disposed longitudinally below the supporting arm, hooks on the supporting 115 arm, and flexible connections at the ends of said cradle and extending upward to said hooks.

3. The combination with a bed post, of a swinging cradle support therefor comprising a supporting arm tubular at one end, a brace extending downward and inward from the outer end of the arm and being formed 125

at its inner end to partially embrace the bed post, a bed post clamp formed in two sections adapted to embrace and have rotation upon the bed post, the two sections being 5 formed with screw threaded shanks engaging with the threaded end of the arm, and a cradle swingingly supported from said arm, said brace acting to prevent a rotation of the

supporting arm relative to the clamp until the brace is detached from the bed post. 10

In testimony whereof I hereunto affix my signature in the presence of two witnesses.

GEORGE HOLMES COCKS.
